UNITED STATES PATENT OFFICE.

RAYMOND CAMILLE MARIE DE BERCEGOL, OF LISIEUX, FRANCE.

DEVICE ALLOWING THE RAPID AND CONTINUOUS DRAWING OF PARALLEL LINES OR BANDS, ESPECIALLY IN VIEW OF MAKING POLYCHROMATIC SCREENS FOR COLOR PHOTOGRAPHY.

Original application filed December 2, 1922, Serial No. 604,548, and in France December 5, 1921. Divided and this application filed September 3, 1924. Serial No. 735,719.

This application is a divisional of my co-pending application filed Dec. 2, 1922, Ser. 604,548.

One of the different means priorly proposed for establishing screens with polychromatic divisions in color-photography, 5 consists in automatically situating the three required colors by means of a successive drawing or tracing of parallel furrows or 10 grooves in a transparent sheet which has been previously covered with one of these colors. These grooves uncover the inner, non-colored part of the support and allow, due to an insulating agent previously spread 15 over the whole surface, to color only, without any registering, the parts which have been thus uncovered.

The gelatine, which is the only insulating medium proposed for obtaining the result in 20 taking as a support a sheet of celluloid or a coat of collodion spread upon glass, has the serious disadvantage to dry very slowly and to render it impossible to make rapidly the three-color screen, a very long pause intervening between each run. Furthermore it 25 offers a certain resistance to the drawing tool. The disadvantage, even at a less degree, still exists when making use of varnishes or gums and some of the latter show, 30 besides this, the disadvantage of making it impossible to draw or dig hollow plain lines.

The present invention has for its purpose to remedy these serious disadvantages and to allow, namely by means of the very simple 35 device which will be hereinafter described, to make the three series of microscopic colored elements, in the support itself, in a single operation comprising, it is true, several runs, but being effected without any interruption, so that a film, without any color 40 for instance, can be within a few minutes, for a single machine, converted into a three-color screen capable of being used for the color-photography.

The present invention consists essentially 45 in replacing the gelatine or the varnishes by a substance which is impervious to water or alcohol and is soft such as: wax, tallow, paraffine, stearine, etc. according to the color 50 used which thus constitutes, no longer a varnish, but a more or less soft coating, which can be spread if necessary by simple con-

tact or by rubbing and capable at once to act as a provisory protector of the colors already absorbed by the support. Accord- 55 ing to this new process nothing hinders the operations to take place one after the other, without any interruption, which means an advantage of a very great industrial interest. Moreover the drawing tool can easily 60 enter this soft coating.

This principle can be carried out by means of the device which is hereinafter described and schematically represented in Figure 1 of the drawing given by way of example, 65 and can be used for making rapidly screens with polychromatic divisions.

Figs. 1 and 1^a are plan views of left and right portions respectively of a preferred 70 form of the invention;

Fig. 2 is a side elevation of the portion of the machine illustrated in Fig. 1;

Fig. 3 is a modification of the means for removing portions of the film coating;

Fig. 4 is a front elevation of devices 75 shown in Fig. 3;

Figs. 5 to 9 illustrate further modifications of the coating removing means.

Supposing, for example, it is wanted, to make a netting composed of small juxtaposed elements of the three selected colors: 80 orange-red, green and violet-blue, in the thickness of a film as used for photography or cinematography.

The colorless film *a*, placed upon a moving 85 apron, is first covered over its whole surface, by means of a distributing device *b*¹ of any construction, of an orange-red coloring matter dissolved in alcohol for example. After having moved during the time which 90 is necessary to allow this color to soak sufficiently (a few seconds), this film is submitted to the action of a water spray *c*¹ which drives out the excess of color and to that of a blower *d*¹ which dries the same. A roller 95 *e*¹ (or a pad or any suitable similar device) spreads over the whole surface, for instance a very thin layer of wax in its natural state or softened in a dissolving agent, which is at once evaporated; this layer or coating is at 100 once ready to perform its duty as an insulating medium.

A tool *f*¹ with multiple microscopic teeth, hereinafter described in detail, draws shal-

low parallel furrows or grooves in the film through the relatively soft layer or coating and thus removes a portion of the coating of the support. The part a^1 of the film thus prepared and still carrying on to move receives the green color supplied from a feeder b^2 and also dissolved in alcohol which, although being spread over the whole surface, only locates itself in these grooves without interfering with the interspaces protected by the wax. The excess of this color is driven away a little further, as already stated, by a spray c^2 , the film being then dried by a blower d^2 . The film continuing to advance is again covered with wax by a roller e^2 and just after can be submitted to the action of a second tool f^2 with multiple teeth making grooves at right angle to the first ones or interposed between the latter. Since this tool removes portions of the colored superficial coating from the film, it will be understood that the spreading of the violet-blue over the whole surface will cause only the coloration of the second series of grooves or furrows and that after washing and drying, the three-color netting will be constituted without any colorless interval or any superposition, as suitable when the film comes to the end of its motion. It would be possible, by the same means, to locate four or five different colors.

If gelatine is used for the support, it is then necessary to use as insulating agent, tallow, grease, etc.

The process can also be used for making three-color screens on glass coated with gelatine or collodion.

Figures 3 to 8 show different constructions of a mechanical device with continuous motion especially devised for the industrial preparation of the above stated screens, but also capable of being applied to many other uses.

This device has for its purpose to draw very quickly either bands, or parallel grooves or hollows, whatever the thinness of the same may be.

It is particularly adapted for working upon soft sheets (photographic films, papers, etc.) but can also be used for drawing upon rigid surfaces.

It allows namely to cross lines diagonally at any angle, this arrangement being the most suitable for the netted screens used in color-photography.

The device is essentially composed of: 1st, two wheels g , h , or a greater number of same, preferably horizontally arranged and connected together by a sort of endless saw i (band saw) for which no path has been provided; 2nd, of a carriage j , or moving apron, the advance motion of which depends strictly on that of the said wheels, through the roller k and the gears l , for example, and arranged parallelly to these wheels, so

that the teeth of the saw come in contact with the surface thereof. Rollers m prevent any deflection of the band.

Figures 3 and 4 show schematically the essential parts of the device in its most common form. The photographic film a moves over the carriage j and the teeth of the saw i dig during its passage distinct grooves or hollows therein. In fact, in virtue of the advancing motion of the film, each tooth draws its line in parallelism to that of the preceding tooth and the result is the formation of continuous grooves which are but slightly deflected, but all parallel. Figure 3 shows this tracing in n , the intervals being exaggerated for the sake of more clearness.

The width and the number of these lines, as well as their interspacing, can be regulated at will. In fact, the width depends on that of the teeth which can be thinned as such as wanted by means of a lateral sharpening; the number and the interval depend on the ratio between the speeds of the saw and the apron and also the number of teeth.

If it is desired to draw two series of parallel grooves or lines diagonally of different width and intersecting each other so as to make a quadrille, it is only necessary to dispose obliquely and in a reverse direction on the path of the apron, two similar devices provided with tools suited to the widths which are to be obtained, Fig. 5. In this case, in order that the teeth of the band reach the sheet only once for every turn, the wheels or the apron can be slightly inclined.

However, if the lines or grooves are to be of the same width, a single toothed band guided by three or four rollers, as indicated by the schematic views 7 and 8, will draw still more simply the same kind of lines, the teeth acting at A and A' according to two different directions.

Finally, when a drawing of curved lines is useful or without any inconvenience, the device can be simplified in using a single wheel or arms carrying at the periphery, either the toothed band or the drawing tools, Figure 6. This figure shows four tools o secured to the rim of the wheel.

In this case the tool can consist of a flexible needle or pin abutting against the very thin edge of the rule lying flat upon the film.

The schemes 3 to 8 serve only to show the kind of drawings or tracings which the machine can make. It is well understood that, in any case, the motion of the tools and the motion of the sheet to be ruled can be made dependent the one on the other.

It is obvious that the same band guided by rollers could pass again over the apron many times according to any directions and thus draw various regular figures.

Although it would be difficult to obtain with this modification a continuous operation, there can also be provided a fixed apron, the wheels and the tool-carrying band having simultaneously imparted thereto a circular and a progressive motion.

I claim:

1. In an apparatus for forming a polychrome film, means for longitudinally advancing said film, a plurality of color spreaders, a coating device disposed between adjacent spreaders, and a groove forming tool disposed between each coating device and the next succeeding spreader in the direction of the advance of said film.
- 15 2. In an apparatus as claimed in claim 1,

the combination with washing and drying devices adjacent each spreader.

3. In an apparatus as claimed in claim 1, said tool comprising a plurality of cutting elements moving over said film in directions at right angles to each other and angularly with respect to the direction of movement of said film.

The foregoing specification of my "Process and device allowing the rapid and continuous drawing of parallel lines or bands, especially in view of making polychromatic screens for the color-photography" signed by me this 20th day of August, 1924.

RAYMOND CAMILLE MARIE de BERCEGOL.
